(57) CLAIM

The ornamental design for a camp cart, as shown and described.

DESCRIPTION

FIG. 1 is a front, right, top perspective view of a camp cart, showing my new design;

FIG. 2 is a rear, left, bottom perspective view thereof;
FIG. 3 is a rear, right perspective view of the enlarged scale thereof;

FIG. 4 is a rear, right, top perspective view of the enlarged scale thereof;

FIG. 5 is a front elevational view of the enlarged scale thereof;

FIG. 6 is a rear elevational view of the enlarged scale thereof;

FIG. 7 is a left side view of the enlarged scale thereof;

FIG. 8 is a right side view of the enlarged scale thereof;

FIG. 9 is a top plan view of the enlarged scale thereof;

FIG. 10 is a bottom plan view of the enlarged scale thereof;

FIG. 11 is an enlarged view of detail 11 in FIG. 1;

FIG. 12 is an enlarged view of detail 12 in FIG. 1;

FIG. 13 is an enlarged view of detail 13 in FIG. 1;

FIG. 14 is an enlarged view of detail 14 in FIG. 1;

FIG. 15 is an enlarged view of detail 15 in FIG. 1;

FIG. 16 is an enlarged view of detail 16 in FIG. 2;

FIG. 17 is an enlarged view of detail 17 in FIG. 2;

FIG. 18 is an enlarged view of detail 18 in FIG. 2;

FIG. 19 is an enlarged view of detail 19 in FIG. 2;

FIG. 20 is an enlarged view of detail 20 in FIG. 2;

FIG. 21 is an enlarged view of detail 21 in FIG. 3;

FIG. 22 is an enlarged view of detail 22 in FIG. 3;

FIG. 23 is an enlarged view of detail 23 in FIG. 4;

FIG. 24 is an enlarged view of detail 24 in FIG. 4;

FIG. 25 is an enlarged view of detail 25 in FIG. 5;

FIG. 26 is an enlarged view of detail 26 in FIG. 6;

FIG. 27 is an enlarged view of detail 27 in FIG. 6;

FIG. 28 is an enlarged view of detail 28 in FIG. 7;

FIG. 29 is an enlarged view of detail 29 in FIG. 7;

FIG. 30 is an enlarged view of detail 30 in FIG. 9;

FIG. 31 is an enlarged view of detail 31 in FIG. 9;

FIG. 32 is an enlarged view of detail 32 in FIG. 9;

FIG. 33 is an enlarged view of detail 33 in FIG. 10;

FIG. 34 is an enlarged view of detail 34 in FIG. 10; and, FIG. 35 is an enlarged view of detail 35 in FIG. 10. The dashed broken lines in the figures are for the purposes of illustrating portions of the camp cart and form no part of the claimed design. The dash-dot-dash broken lines are for notating enlarged views and form no part of the claimed design.

1 Claim, 35 Drawing Sheets
